UNITED STATES PATENT OFFICE.

WARREN B. LOOK, OF JAMESTOWN, NEW YORK, ASSIGNOR TO ART METAL CONSTRUCTION COMPANY, OF JAMESTOWN, NEW YORK, A CORPORATION OF NEW YORK.

LIBRARY-STACK CONSTRUCTION.

1,195,374.

Specification of Letters Patent. Patented Aug. 22, 1916.

Application filed August 10, 1914. Serial No. 856,048.

To all whom it may concern:

Be it known that I, WARREN B. LOOK, a citizen of the United States, residing at Jamestown, in the county of Chautauqua and State of New York, have invented certain new and useful Improvements in Library-Stack Constructions, of which the following is a specification.

The object of this invention is to provide an improved form of library stack for a support for book shelves, floors, etc., in fire proof library construction.

Another object of the invention is to make the support entirely of sheet metal bent to the required form, the supports being made of uprights arranged in pairs, the uprights to be rounded or otherwise suitably connected at their meeting edges.

These and other objects of the invention will be fully illustrated in the drawings, described in the specification and pointed out in the claims at the end thereof.

In the accompanying drawings, Figure 1 is a perspective view of my improved stack construction. Fig. 2 is a horizontal section on the line 2^x-2^x of Fig. 1. Fig. 3 is a detail view of the end of one of the book shelves. Fig. 4 is a section on the line 4^x-4^x of Fig. 2. Fig. 5 is an elevation 30 of a portion of the stack showing the joint between two consecutive sections, the sections being partly broken away. Fig. 6 is a sectional view on the line 6^x-6^x of Fig. 5 showing a modification of the uprights. Fig. 7 is a perspective view of a portion of the top of a section showing the recess to receive the supporting bar.

In the accompanying drawings, like reference numerals indicate like parts.

40 In the drawings the uprights are shown made up of the main sections 2 and the auxiliary sections 3 and 4 attached to the main section.

The main sections are cross shaped in cross section and are made up of two channels, each of which channels may be made of a single piece of sheet metal as is shown in Fig. 6 or may be made of two pieces of sheet metal as shown in Figs. 1 and 2.

50 Each channel is formed with a long narrow U-shaped portion indicated at 5 in Fig. 6. Extending at right angles thereto are the flanges 7 and 8, which flanges are beveled at 9 and 10 and terminate with the flanges 11 and 12, which flanges are preferably par-

allel to the flanges 7 and 8. Two channels are formed in this manner and their meeting edges are brought together and are fastened together in any suitable manner but preferably by electric welding.

As is shown in Figs. 1 and 2, each section may be made up of four angles instead of two channels, two of the angles going together to form one of the channels shown in Fig. 6, this form of construction being somewhat more desirable because a narrower piece of metal can be used, these narrow sheets being more easily handled in the bending operation through which they must pass.

It will be understood that each of the main sections and the auxiliary sections are made of standard lengths, preferably equal in length to the distance from one floor to another in the finished stack. The sections are assembled to make the stack by putting one section on top of another. The assembling of these sections and the connecting of them together vertically will now be described.

Each of the main sections is formed of flat abutting edges so that they may come directly into contact with each other so that the one section will properly support the next one above it. Each of the main sections is cut away at the top and bottom thereof and on opposite sides thereof to receive the cross bar 13. The flanges 7 and 8 of the channels are separated from each other as shown in Fig. 6 by the space sufficient to receive the bar 13. The flanges 7 and 8 are fastened to the bar 13 by means of the bolts 14 and 15, 16 and 17. The bar 13 is wide enough to build the recesses exposed by the cutaway part at the top of the lower section and at the bottom of the upper section in each case where two sections come together. It will thus be seen that the upper and lower sections at each joint are interlocked with the bar 13 and are held in line therewith and with each other. It will also be seen that the auxiliary sections 3 and 4 are cut away at the ends thereof to receive the bar 13 and are interlocked therewith and are thereby held in line with the bar and with each other.

The auxiliary sections 3 and 4 are slotted at 18 for the purpose of receiving the shelf 19, which shelf is made up of a single sheet of metal and has the channel flange 20 on

its forward edge and a channel flange 21 on its rearward edge, both of which flanges have substantially the same cross section. The shelf is of reduced length at 27 so that 5 it will exactly fit the space between the auxiliary sections 3, 3 or 4, 4, as shown in Fig. 1. A somewhat longer forward part of the shelf being adapted to engage with the slots 18, 18 with the rear ends of which the shoulders 10 28 on the shelves make positive contact.

The bar 13 is perforated to receive the bar 29, which bar extends consecutively through a series of uprights. This bar is surrounded by the sleeve 30 which bears 15 positively against the bar 13, the main sections being perforated to receive both the sleeve and the bar. The bar 29 and sleeve 30 are positively secured at the outer ends of the completed stack in any suitable manner to prevent longitudinal movement thereof 20 thus positively tying all of the parts together.

The bars 13 are intended to support the platform on which the library attendants 25 can pass from one set of shelves to another so as to obtain access to the books. These bars may be of sufficient length to merely support a single gallery or they may extend to a series of uprights thus fastening a 30 number of uprights together transversely in the same way as the bar 29 will fasten the uprights together longitudinally.

In Figs. 1 and 4 I have shown a modification 35 of the structure in which the flat interlocking bar 40 is substituted for the round bar 29. The bar 40 extends across the main sections 2 and extends beyond each side of the main section about an inch. The ends of the bar 40 are perforated. The ends of 40 the bar 40 in consecutive uprights and on the same floors, are connected by the angles 41 which are bolted or riveted thereto. Diagonal braces 43 may also be used to connect the bars 40 in consecutive uprights on 45 adjacent floors. The bar 40 is cut away at 42 to receive the bar 13 with which it interlocks.

I claim:

1. An upright support comprising a channel 50 having a wide flange on each side thereof, each of said flanges having two parallel surfaces, two of said channels being combined to form a cross shaped channel, said channels having the outer flanges thereof partly cut away at the ends thereof, a bar 55 inserted between the inner flanges of consecutive sections and being overlapped thereby.

2. An upright support comprising a series 60 of cross shaped hollow channels arranged one on top of another in series with their ends in direct abutment and their hollow spaces in alinement, a bar nested in and extending across the abutting ends of two of said channels, said bar interlocking with and 65 holding said channels in line with each other

and being supported thereby, a second bar extending transversely through said first named bar and interlocked with the channels above and below said first bar.

3. An upright support comprising a series 70 of cross shaped hollow channels arranged one on top of another in series with their ends in direct abutment and their hollow spaces in alinement, a bar nested in and extending across the abutting ends of two of said channels, said bar interlocking with and 75 holding said channels in line with each other and being supported thereby, a second bar extending transversely through said first named bar and interlocked with the channels above and below said first bar, sleeves 80 on said second bar, the ends of said sleeves abutting against two consecutive ones of the first named bars.

4. An upright support comprising a channel 85 having a wide flange on each side thereof, each of said flanges having two parallel surfaces, two of said channels being combined to form a cross shaped channel, said channels having the outer flanges thereof 90 partly cut away at the ends thereof, a bar inserted between the inner flanges of consecutive sections and being overlapped thereby, channels having narrow flanges thereon 95 fastened to said first named channels and extending transversely thereto.

5. An upright support comprising a channel 100 having a wide flange on each side thereof, each of said flanges having two parallel surfaces, two of said channels being combined to form a cross shaped channel, said channels having the outer flanges thereof 105 partly cut away at the ends thereof, a bar inserted between the inner flanges of consecutive sections and being overlapped thereby, channels having narrow flanges thereon 110 fastened to said first named channels and extending transversely thereto, slots in said channels, shelves adapted to engage with said slots.

6. A library upright support comprising 115 two small channels and two large channels, two flanges on each of said channels, the flanges of said smaller channels that are opposite each other being joined together and the flanges of said larger channels being fastened to the sides of said smaller channels, embracing the joint between the flanges of 120 said smaller channels.

7. An upright support comprising a series 120 of angles arranged one on top of another, each of said angles having two flanges opposite to and in line with each other, each of said flanges having a flange thereon out of line with and parallel thereto, a supporting 125 bar nested between two adjacent sections, said bar passing between and being fastened to the parallel flanges.

8. A section for library stack comprising 130 a pair of channels having flanges thereon

the opposite sides thereof and in line with each other, each of said flanges having a flange thereon out of line with and parallel thereto, said channels being connected by 5 said last named flanges, said section being recessed at the ends thereof by cutting away a part of said last named flanges.

9. An upright support comprising a series of cross shaped hollow channels arranged one on top of another in series with their ends in direct abutment and their hollow spaces in alinement, a horizontal bar nested between the sides of and extending along the abutting edges of two of said channels, said bar interlocking with and holding said channels in line with each other and being supported thereby, the sides of the channels overlapping both sides of the bar and concealing the bar between them, said 15 channels being cut away at their corners to form a recess to receive and support the bar.

10. An upright support comprising a series of channels arranged one on top of another with their ends in direct alinement, a 20 horizontal bar nested between the sides of said channels and passing transversely through the hollow casing formed by said channels and interlocking the adjacent ends of two of said channels, the ends of said 25 channels abutting against each other on both sides of said bar.

11. An upright support comprising a series of channels arranged one on top of another with their ends in direct alinement, a horizontal bar nested between the sides of 35 and interlocking the adjacent ends of two of said channels, the ends of said channels abutting against each other on both sides of said bar, said bar being parallel to two flanges of said channels and holding the 40 abutting edges in alinement in one direction and bolts passing through said bar and said flanges to hold them in alinement in the transverse direction.

12. In an upright support the combination of a central member, said member comprising two channels abutting each other, two additional channels fastened to said central member, one on each side thereof and embracing said channels forming said central support, two bars nested in said channels along the abutting edges of said channels and passing through said channels at right angles to each other, said bars intersecting inside of the channels.

In testimony whereof I affix my signature in presence of two witnesses.

WARREN B. LOOK.
